UNITED STATES PATENT OFFICE.

CHARLES F. BEAMAN, OF CHICAGO, ILLINOIS, ASSIGNOR TO THE WELLSVILLE PLATE AND SHEET IRON COMPANY, OF WELLSVILLE, OHIO.

MACHINE FOR BENDING WIRE.

SPECIFICATION forming part of Letters Patent No. 296,269, dated April 1, 1884.

Application filed February 9, 1884. (No model.)

To all whom it may concern:

Be it known that I, CHARLES F. BEAMAN, of Chicago, in the county of Cook and State of Illinois, a citizen of the United States, temporarily residing at Wellsville, county of Columbiana, State of Ohio, have invented or discovered a new and useful Improvement in Machines for Bending Wire; and I do hereby declare the following to be a full, clear, concise, and exact description thereof, reference being had to the accompanying drawings, making a part of this specification, in which—like letters indicating like parts—

Figure 1 is a view in elevation of one end of my machine. Fig. 2 is a top plan view of the same, the drop-hammer being removed. Fig. 3 is a detail view of the tension device.

The object of my invention is to so bend continuous lengths of wire that regular shapes may be produced by cutting the bent wire at regular intervals; and to this end my invention consists in the construction and combination of parts, all as more fully hereinafter described and claimed.

In suitable bearings, *a*, secured to the bed *A*, is mounted the shaft *B*, and on this shaft *B*, between the bearings *a*, is mounted the gear-wheel *D*, said shaft and gear-wheel being so connected together by a spline on the gear-wheel and a groove, *b*, in the shaft *B* that the shaft will revolve with the gear-wheel, and will also move longitudinally through it. The inner end of the shaft *B* is screw-threaded, as shown at *b'*, and passes between the two parts *c c* of a divided nut, *C*. The parts *c c* of the divided nut are mounted in ways in a block, *d*, and adapted to slide toward and from each other therein.

In the top of the parts *c c* of the divided nut are formed the slots *c'*, and in these slots play pins depending from the ends of the cross-arm *e'* of the lever *e*. By moving this lever *e* to the right or left the parts *c c* of the divided nut are moved from or toward and against the threaded shaft *B*. By the use of a divided nut I am enabled to move the shaft *B* in or out quickly when desired. The outer end of the shaft *B* is supported by a U-shaped bearing at the end of the swinging arm *f*, pivoted to the under side of the table or bed *A*. This swinging arm *f* is held in position for

supporting the shaft *B* by a hook, *g*, also pivoted to the table.

On the shaft *B* is detachably secured the former *H*, which in this case is rectangular in shape, and consists of a cast-iron hub, *h*, on the ends of which are formed the disks *h'*, said disks being connected by the cross-arms *h''*. The outer faces of these arms *h''* are recessed to receive the steel strips *h'''*, which are secured therein by screws or any other suitable means. The former is secured to the shaft *B* by set-screws or any other equivalent device.

At one end of the table *A*, on each side of a recess, *A'*, formed therein, in which the former *H* revolves, are secured the standards *l l'*, which serve as guides to the reciprocating hammer *L*, which is provided with wings *m*, which overlap the flanges *l''* of the standards *l l'*. The distance between the standards *l l'* is greater than the width of the hammer and its wings, thereby allowing of a slight lateral oscillation of the hammer during its vertical movements. The hammer *L* is connected to the standard *l'* by the arms *n*, pivoted at their ends to the hammer and standard, respectively.

To a bracket, *O*, are secured a tension device, *o*, and straightening devices *p*, and the wire to be bent is led from a suitably-located reel through the tension and straightening devices, and through an opening in the standard *l'* to the former, around which it is to be bent. The power-wheel *R* is loosely mounted on a shaft, *r*, mounted in bearings *s*, bolted to the bed *A*, and on the shaft *r* is secured a spur-wheel, *S*, which meshes with the gear-wheel *D*. Motion is communicated from the power-wheel *R* to the shaft *r* by a clutch mechanism, *W*, operated by the lever *w*.

The tension device *o* consists of a steel-faced block, *o'*, adjustably secured on the bracket *O*, and a sliding steel-faced block, *o''*, behind which is pivoted a lever, *o'''*, having a cam projection at its lower end, which bears against the block *o''*, and forces said block toward the block *o'* and against the wire between them.

In operating my machine, the end of the wire to be bent is passed between the blocks of the tension device, through the straightening device and through the opening in the standard *l'* to the former, to which it is secured.

The shaft B is slid inward, the parts *c c* of the divided nut being separated for that purpose, until the outer edge of the former is in line with the wire as it comes from the straightening device. The parts of the divided nut are then forced together around the threaded shaft and the machine started by moving the clutch into engagement with the power-wheel, which is driven by any suitable means. As the former revolves and winds the wire around itself, the operator holds the wire with sufficient tension by the tension device to cause the wire to be tightly bound around the former. The corners of the former in its revolutions raise the hammer L, and as the revolution of the former is quite rapid the hammer will, when the corners of the former move downward and leave the face of the hammer, drop upon the flat sides of said former, flattening the wire against the sides of the former. The hammer when it strikes the former rebounds a slight distance, and before it can again descend the next succeeding corner of the former will strike the face of the hammer and again fully raise it. This blow which the ascending corner of the former gives to the hammer has the effect of bending the wire around said corner, and as the wire at this corner rubs along the face of the hammer in raising it the wire will be forced sharply around said corner. It will be noticed that as the hammer is pivotally connected to the standard *l* it will have while being raised a slight horizontal movement in a direction contrary to that in which the former is rotated. This movement aids in bending the wire around the corner which is raising the hammer. After the former has been filled with wire, the machine is stopped, the bearing arm *f* is swung to one side, and the former removed from the shaft B. The divided nut is then opened, the shaft B is pushed inward the proper distance, and another former is secured on the shaft, when the machine is again ready for operation.

The flanges *l* of the standards are necessary only on the outside of the wings of the hammer, to prevent the hammer from being carried along with the former as it is forced outward by the threads on the shaft working through the nut C. These flanges might be dispensed with; but I prefer to employ them, as they relieve the arms *n* of any lateral strain. The threads of the shaft and nut are given such a pitch that the former is thrust outward at each revolution a little more than the diameter of the wire. By thus feeding forward the former I remove all liability of one coil of the wire being wound upon the preceding one, which is liable to occur when the former and the devices from which the wire is drawn are stationary.

I am aware that it is old to use a heavy pivoted lever in connection with a revolving form-

er; but in such a device the wire is caused to conform with the shape of the former by a continuous uniform pressure, whereas in my machine the wire is subjected to sharp blows, which are effective to bend the wire beyond the limit of elasticity, and consequently give it a permanent set. After the former is removed from the shaft B, the bent wire is stripped from the former, and is cut in one of its sides, thereby producing a blank ready to be incorporated in the rim of a pan.

Formers having shapes other than that shown may be used; but in case a round former is used some device should be added thereto which will operate to raise the hammer in a manner similar to the corners of the former shown.

I claim herein as my invention—

1. In a machine for bending wire, a rotating former, in combination with a drop-hammer, said parts being so constructed and arranged that the wire is made to conform to the shape of the former by a series of blows, substantially as set forth.

2. In a machine for bending wire, a rotating and longitudinally-movable former, in combination with a drop-hammer, substantially as described.

3. In a machine for bending wire, the former H and the shaft B, threaded and grooved at one end, in combination with the gear-wheel D, splined to said shaft, divided nut C, and means for opening and closing the divided nut, substantially as set forth.

4. In a machine for bending wire, the former H, detachably secured to the shaft B, in combination with the swinging bearing-arm *f*, substantially as set forth.

5. In a machine for bending wire, the former H, secured to the rotating and longitudinally-movable shaft B, in combination with the tension device *o* and the straightening device *p*, substantially as set forth.

6. In a machine for bending wire, the rotating and longitudinally-movable former H, in combination with the drop-hammer L, having the wings *m*, the guide-standards *l l'*, having the flanges *l*, and the arms *n*, substantially as set forth.

7. In a machine for bending wire, the drop-hammer L, having side wings, *m*, in combination with the standards *l l'*, so arranged as to allow a slight horizontal movement to the hammer during its vertical reciprocation, the arms *n*, pivotally connected to the hammer and the standard *l*, and the former, substantially as set forth.

In testimony whereof I have hereunto set my hand.

CHARLES F. BEAMAN.
